UNITED STATES PATENT OFFICE

FRANKLIN B. HUNT, OF CHICAGO, ILLINOIS, ASSIGNOR, BY MESNE ASSIGNMENTS, TO THE LIQUID CARBONIC CORPORATION, OF CHICAGO, ILLINOIS, A CORPORATION OF DELAWARE

SODA FOUNTAIN

Application filed April 20, 1925. Serial No. 24,333.

This invention relates to improvements in soda fountains adapted for use in ice cream parlors, drug stores, and other like places. The principal object of the invention is to provide an improved cooling system whereby with the use of a single cooling unit different temperatures are obtained in different compartments of the soda fountain cabinet. A further object of the invention is to provide means for obtaining in one compartment of the cabinet a relatively low temperature for brick ice cream and in another compartment of the cabinet a higher temperature adapted for bulk ice cream, these different temperatures being produced by the operation of a single cooling unit. Still another object of the invention is to provide improved means in a soda fountain for controlling the transfer of heat from one compartment of the cabinet to another. A further object of the invention is to provide means for controlling the circulation of the brine in a compartment of the soda fountain cabinet. Other objects relate to various features of construction and arrangement which will appear more fully hereinafter.

The nature of the invention will be understood from the following specification taken with the accompanying drawings in which one embodiment is illustrated. In the drawings, Fig. 1 shows a somewhat diagrammatic front elevation and perspective view of a soda fountain embodying the features of the present invention including the cooling system thereof; Fig. 2 shows a horizontal section through the soda fountain cabinet illustrating the arrangement of the compartments and the ice cream containers therein; Fig. 3 shows a vertical section on the line 3—3 of Fig. 2; Fig. 4 is a longitudinal section through a portion of the evaporator or boiler; Fig. 5 shows an end elevation of the boiler or evaporator illustrated in Fig. 4; and Fig. 6 shows somewhat diagrammatically the means for controlling the operation of the refrigerating system.

The embodiment of the invention illustrated in the drawings comprises a soda fountain 10 having a front wall 11 and end walls 12 supporting a top railing or counter 13.

The enclosure formed by these walls has located therein the cooler cabinet 15 provided with a horizontal top wall or capping 16, provided with a flange 16^a, extending downwardly at the rear of the rear wall 17. The end walls 12 of the soda fountain may form the end walls of the cooler cabinet and the front wall 11 may similarly form the front wall of the cabinet.

The cabinet 15 contains a casing 20 of sheet metal comprising a lower wall 21, end walls 22, a front wall 23 and a rear wall 24. This closed casing 20 is insulated from the surrounding walls of the cabinet by means of insulating material 25 and is also insulated from the top capping 16 by insulating material 26. The casing 20 is divided by a vertical partition 27 thus forming two separate compartments 28 and 29, each of which is filled preferably with a suitable brine such as a solution of calcium chloride and water. The brine in the compartment 28 surrounds a receptacle 30 of rectangular cross-section which is adapted to contain brick ice cream and which is located directly beneath an opening in the top capping 16 which is normally closed by a removable cover 31. The brine solution in the compartment 29 surrounds a plurality of containers 32 of elliptical horizontal cross-section each of which is adapted to receive a pair of cylindrical receptacles 33 for bulk ice cream. The containers 32 are spaced from each other and from the walls of the casing 20 so that they are entirely surrounded by the brine. The receptacles 32 are located beneath openings in the top capping 16 and these openings are normally closed by covers 35 each comprising a pair of hinged lids 36 adapted to permit access to either one of the receptacles 33 located in one of the containers 32. A plurality of containers 37 for fruit juices, flavoring extracts and the like are located beneath and at the rear of the counter 13 on opposite sides of the nozzles 38 which are adapted to discharge fresh water and carbonated water.

The compartments 28 and 29 are cooled by the operation of a boiler or evaporator 40 which is located in the compartment 28 and 100

connected with suitable mechanism for effecting the supply thereto of a liquefied refrigerant. The brine in the compartment 29 is cooled by the transfer of heat through 5 the partition wall 27 to the compartment 28 in which the boiler or evaporator 40 is located. This transfer of heat results in the setting up of convection currents in the bodies of brine in the two separate compartments of the cabinet. Due partly to the 10 heat insulating effect of the partition wall 27 which may be formed preferably of copper, and more largely to the effect of the film on the surfaces of the partition, known 15 as "surface effect," a difference in temperature is maintained between the brine in the compartment 28 and the brine in the compartment 29. For example, the temperature in the compartment 28 may be maintained 20 at zero degrees Fahrenheit while the temperature of the brine in the compartment 29 may be 6 or 8 degrees Fahrenheit warmer. This condition is suitable for the maintenance 25 of the proper temperatures of the bulk and brick ice cream since the bulk ice cream which is normally served over the counter must not be too hard while the brick ice cream, which is usually sent out to the home of the customer, must be maintained at a 30 much lower temperature so that it will maintain its low temperature for a longer period after being delivered from the soda fountain.

If desired, a greater difference in temperature 35 between the two compartments of the cabinet may be brought about by the use of one or more additional partitions which may be either complete or partial partitions. In the drawings, there is illustrated a partial 40 partition or baffle 41 formed of sheet metal, such as copper, which extends between the front and rear walls of the casing 20 and which extends downwardly from the top wall thereof throughout only a part of the 45 depth of the casing. In this instance, it is shown as extending substantially through one-half of the depth of the casing and is spaced somewhat from the adjacent partition wall 27 and also from the adjacent 50 container 32. In this construction, the heat which passes through the upper portion of the partition must pass through two sheet metal walls and overcome four surface films in addition to setting up a small convection 55 current cycle in the brine which is located between the wall 41 and the wall 27. This tends to decrease the rate of heat transfer between the two compartments so that a greater temperature difference may be maintained. The temperature difference may be 60 regulated as desired by varying the area and number of the baffle walls or partitions 41. The temperature difference is also affected to some extent by a baffle wall 42 which extends upwardly from the bottom 65

wall 21 of the casing 20 in alignment with the longitudinal axis of the container 32 which is located nearest to the partition wall 27. This baffle wall 42, which is formed in two sections, unites the front and rear walls 70 of the casing 20 with the curved end walls of the container 32 so that the convection currents set up in the brine in the compartment 29 are compelled to pass over these baffle walls 42 as the cooled brines passes upwardly away from the partition 27. These baffle walls have the desirable effect of deflecting the convection currents upwardly from the lower part of the partition wall 27 so that they tend to direct these currents toward the 75 upper parts of the containers 32 in the compartment 29 thereby cooling the upper portions of the containers which are most likely to be affected by the temperature of the outer air and causing a more uniform temperature to be maintained throughout the 80 depth of the containers 32.

The brine solution in the compartment 28 is cooled by the vaporization in the boiler 40 of a suitable refrigerant, such as sulphur 90 dioxide (SO_2) which is passed into the boiler in liquid form and which vaporizes therein with a resulting cooling of the surrounding brine solution. The boiler 40 comprises a horizontal cylinder 46 having extending 95 downwardly therefrom a plurality of circulating tubes 47 as shown particularly in Figs. 4 and 5. The tubes 47 extend downwardly from the cylinder 46 into the brine solution and as the sulphur dioxide boils or 100 vaporizes, the liquid refrigerant circulates through these tubes and reduces the temperature of the surrounding brine solution. The cylinder 46 of the boiler has a vapor space 48 located above the level of the sulphur dioxide which is shown at 49. The liquid refrigerant is supplied to the cylinder 46 of the boiler through a supply pipe 50 and the level of the refrigerant 49 is maintained by means of a float 51 pivoted at 52 105 on the end wall of the cylinder and connected by links 53 with a valve 54 which is adapted to engage a valve seat 55 to stop the in-flow of the liquid refrigerant when the level has raised to the desired extent within 110 the cylinder of the boiler. The vaporized sulphur dioxide, or other refrigerant, is drawn off through a pipe 56 to the compressor 60 which is driven by an electric motor 61. The vaporized refrigerant is 115 forced by the compressor 60 through a pipe 62 into the condenser 63 which may be cooled in any desired manner and is shown as having located therein a cooling coil 64 through which cold water or other fluid is 120 circulated, from a supply pipe 65, the water or other fluid being discharged through a pipe 66. The flow of cold water through the coil 64 may be regulated in any desired manner. A regulating shut-off valve 67 is 125 130

located in the pipe 62 connecting the compressor with the condenser and a shut-off valve 68 may be preferably located in the pipe 56 at the intake of the compressor. 5 The sulphur dioxide vapor, or other vaporized refrigerant, is reduced to a liquid form in the condenser 63 by contact with the circulating pipe 64 and the pressure in the condensing chamber is adapted to force the 10 liquid refrigerant from the bottom of the condenser through an outlet valve 69 to the pipe 50 which conveys it to the cylinder 46 of the boiler 40.

The electric motor 61 is supplied with current through line conductors 70 having connected therein a main cut-off switch 71 and having connected therein, also, an automatic control switch 72 comprising a pair of contacts 73 one of which is stationary and the other of which is mounted on an arm 74 pivoted at 75 on a stationary supporting member 76. The opposite side of the supporting member 76 has pivoted thereon at 77 another arm 78 similar to the arm 74 and the 25 outer ends of these arms are connected by one or more coil springs 79, as shown in Fig. 6. The outer end of the arm 78 is pivotally connected to a rod 80 which extends upwardly and is pivoted at 81 on a lever 82. The 30 lever 82 is engaged on its upper side by a fulcrum 83 carried by a fixed support 84 and the lever is engaged on its under side at a point on the opposite side of the fulcrum 83 from the pivot 81 by a second fulcrum 85 which is carried by a sylphon tube or bellows 86 having communication with a pipe 87 which leads from a thermostatic tube 88 located in the compartment 28 adjacent the boiler 40. The thermostatic tube 88, the pipe 89 and the sylphon bellows 86 are filled with methyl chloride or other liquid adapted to expand on an increase in the temperature of the brine in the compartment 28. When the temperature of the brine rises to a pre-determined extent, the expansion of the sylphon bellows 86 raises the fulcrum 85 with the result that the arm 78 is gradually lowered until the outer end thereof passes slightly beyond a dead center position with respect 45 to the arm 74, whereupon the spring or springs 79 causes the arm 74 to snap downwardly and close the switch contacts 73. When the temperature in the compartment 28 has fallen to the desired extent, the contraction of the bellows 86 under the influence of the thermostatic tube 88, causes the fulcrum 85 to be lowered, with the result that the rod 79 gradually elevates the arm 78 until it passes beyond a dead center position 50 with respect to the arm 74, whereupon the arm 74 snaps upwardly and opens the switch contacts 73, thereby stopping the motor 61 which drives the compressor 60. By means of this construction of the switch 72, a considerable range of temperature may be per-

mitted without causing the switch contacts to open or close, thus avoiding a rapid intermittent operation of the motor and the compressor. The temperatures at which the switch 82 is operated to start and stop the 70 motor may be regulated by a weight 90 mounted on the extension 91 of the lever 82 and secured in adjusted position by a set screw 92. This weight may be moved to any desired position and secured in that position by the operation of the set screw so that the subsequent control of the operation of the motor is entirely automatic. 75

By means of this invention, the temperature of the brine in the compartment 28 containing the receptacle of rectangular cross-section for brick ice cream, is maintained at all times at a desirable low temperature and the provision of one or more partition or baffle walls between compartment 28 and the compartment 29 results in the maintenance of a substantially uniform and somewhat higher temperature in the brine of the compartment 29. 80

I claim:

1. A cooling cabinet for soda fountains comprising a plurality of compartments, a heat-transmitting partition wall separating said compartments, a receptacle in one of said compartments for one class of goods, a 95 receptacle in another of said compartments for another class of goods, and a baffle extending upwardly from the bottom wall of said last mentioned compartment outwardly from said partition wall to control the flow 100 of cooling fluid in communication with said partition wall. 90

2. A cooling cabinet for soda fountains comprising a plurality of compartments, a heat-transmitting partition wall separating adjacent compartments, a baffle wall extending parallel to said partition wall and spaced therefrom in one of said compartments, a fluid cooling medium in said last mentioned compartment contacting with said partition wall and said baffle wall, and refrigerating means located in the other of said compartments. 105 110

3. A cooling cabinet for soda fountains comprising a plurality of compartments, a heat-transmitting partition wall separating adjacent compartments, a baffle wall extending parallel to said partition wall and spaced therefrom in one of said compartments, a fluid cooling medium in said last mentioned compartment contacting with said partition wall and said baffle wall, refrigerating means located in the other of said compartments, and a baffle extending upwardly from the bottom wall of said compartment in which 120 said first-mentioned baffle wall is located. 115

4. A cooling cabinet for soda fountains comprising a plurality of compartments, a heat-transmitting, partition wall separating adjacent compartments, a baffle wall extend-

ing downwardly from the upper wall of one of said compartments and disposed relatively close to said partition wall, a fluid cooling medium in said last mentioned compartment contacting with said partition and baffle walls, and refrigerating means located in the other of said compartments.

5. A cooling cabinet for soda fountains comprising a plurality of compartments, a
10 heat-transmitting, partition wall separating adjacent compartments, a baffle wall extending parallel to said partition wall and spaced therefrom in one of said compartments, a fluid cooling medium in said last mentioned
15 compartment contacting with said partition wall and said baffle wall, refrigerating means located in the other of said compartments, and a baffle extending upwardly from the bottom wall of said compartment in which
20 said first-mentioned baffle wall is located and spaced further from said partition wall than said first baffle wall.

6. A cooling cabinet for soda fountains comprising a plurality of compartments, a
25 heat-transmitting, partition wall separating adjacent compartments, a baffle wall extending downwardly from the upper wall of one of said compartments, a second baffle wall extending upwardly from the bottom wall
30 of said last mentioned compartment, a fluid-cooling medium in said last mentioned compartment contacting with said partition and baffle walls, both of said baffle walls controlling the flow of cooling fluid in communication with said partition wall, and refrigerating means located in the other of said compartments.

7. A cooling cabinet for soda fountains comprising a plurality of compartments, a
40 heat-transmitting, partition wall separating adjacent compartments, a baffle wall extending downwardly from the upper wall of one of said compartments and spaced from said partition wall, a second baffle wall extending
45 upwardly from the bottom wall of said first named compartment and spaced a greater distance from said partition wall than said first named baffle, a fluid-cooling medium in said first named compartment contacting
50 with said partition and baffle walls, both of said baffle walls controlling the flow of cooling fluid in communication with said partition wall, and refrigerating means located in the other of said compartments.

55 FRANKLIN B. HUNT.
